UNITED STATES PATENT OFFICE

CHARLES A. CYPHERS, OF BUFFALO, NEW YORK

SWITCH DEVICE FOR INCUBATORS

Application filed November 14, 1927. Serial No. 233,239.

This invention relates to an automatic heat controlling unit adapted particularly for use in connection with incubators and the like.

To that end the invention contemplates a novel switch or circuit closer of the mercury type possessing special features and characteristics which distinguish it from prior devices both from the standpoint of reliable performance and advantages resulting in its use. Heretofore, mercury switches have not been accurate because it has been customary to pivot the mercury bulb centrally so that the weight resistance incident to the throw-over for the make-and-break increased or decreased the tension on the thermostat. Obviously differential loading conditions on the motive power, namely the thermostat, is undesirable on account of the delicate character of the thermostat, and therefore the present invention contemplates a construction which will function without perceptible change in the tension on the thermostat and will also operate with a minimum of friction.

A further object of the invention is to provide a pendant switch which operates with a free and unhampered pendulum motion or action, thereby providing a simple, reliable and smooth acting controlling means for the circuit which requires practically no attention after once being set, and which will give good service indefinitely.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which

Figure 1 is a front elevation of the improved device.

Figure 2 is a top plan view thereof.

Figure 3 is an enlarged vertical sectional view taken on the line 3-3 of Fig. 1.

Figure 4 is a view similar to Fig. 3 showing the switch open.

Figure 5 is a detail horizontal sectional view taken on the line 5-5 of Fig. 3.

Similar reference characters designate

corresponding parts throughout the several figures of the drawings.

In its primary aspect the present invention includes in its organization a pendant switch device designated generally as S and a prime mover or actuator in the form of the thermostat T, the latter being connected with the switch device through a suitable lever, as will hereinafter more fully appear.

Referring first to the switch device S it will be observed that the same includes a glass or equivalent insulating bulb 1 having therein the contact members 2 and 3, the former being of elongated formation and lying lengthwise in the bottom of the bulb so that it may always be in contact with the mercury or other shiftable circuit closing medium 4. The said glass bulb 1 is surrounded by an insulation band or member 5 and is carried by the lower looped end 6 of a carrier arm 7 which is pivoted as at 8 to the pendant suspending lever 9 and has the adjustable pin and slot connection 10 with the intermediate part of said lever 9 so that the angular position of the longitudinal axis of the bulb 1 may be changed to suit different installations and conditions of use.

The pendant lever 9 is preferably provided at its upper end with a hub portion 11 so that the said lever is pendulously supported to swing fully on the shaft 12 pivotally mounted in the opposite ears 13 of a bracket 14 by means of the adjustable bearing screws 15. The contacts 2 and 3 are adapted to be connected in series by the mercury 4, and each contact is provided with a circuit wire connection respectively designated as 2^a and 3^a, the former leading to a binding terminal 17 and the latter to a binding terminal 18 to which is connected one of the wires 19 of a service line 20, the other wire 21 of said line being connected to the binding terminal 22. The said terminals 17 and 22 are connected with the heating element, not shown.

The bracket 14 is carried by a suitable support or base B which also carries the insulated block 23 on which the binding terminals referred to are mounted. A guard 24 is also carried by the base for protecting the switch bulb from accidental contact with any

object which might destroy it; and, for the purpose of holding the entire pendulum-like arm 9 in a position where it will not swing, as for example holding it in a position where 5 the circuit will be permanently open when the apparatus is not in use, or to hold it in a fixed position during transportation to prevent damage, a suitable locking pin 25 is provided. This pin is pivotally mounted 10 in the support and is provided with a pair of spaced, laterally offset, arms 26 which are adapted to embrace both sides of the lever 9 to hold it in a rigid position for shipping, or out of contact when lever 9 is resting on 15 the outer arm.

As will be observed from Figs. 3 and 4 the upper portion of the arm 9 has a link 27 connected therewith, the said link being in turn connected with a controlling lever 28 20 which is carried by a plate 29. This plate is pivotally mounted upon a vertically disposed shaft or axis 30 so that it may freely swing in a horizontal plane thereby to move the pendulum-like lever 9 from the position 25 shown in Fig. 3 for instance to the position shown in Fig. 4 to break the circuit, or vice versa.

The plate 29 carries therewith a screw 31 which is adapted to bear against the thermostat T so that when the same expands and contracts, the movement thereof will be imparted directly to the lever 28. Clearly, therefore, as the thermostat contracts the 30 pendulum will move backwards under its own weight to cause the mercury to assume the position shown in Fig. 3 to close the circuit, and on the other hand, when the thermostat expands under heat the lever 28 will be moved away from the support and 35 thus rock the bulb 1 to the position shown in Fig. 4 to open or break the circuit. In changing the relative position of the bulb 1 on the end of the lever 9 by means of adjusting the same on the pivot 8, more or 40 less movement of the lever 28 will be required to move the pendulum to open and close the circuit.

From the foregoing it will be apparent that the present invention provides a novel 45 and distinctive form of mercury switch having a pendulum action, which for the reasons heretofore pointed out, is particularly advantageous for use in connection with a relatively delicate thermostat of the type used 50 on incubators and the like.

Without further description it is thought that the features and advantages of the invention will be readily apparent to those 55 skilled in the art, and it will of course be understood that changes in the form, proportion and minor details of construction may be resorted to, without departing from the spirit of the invention and scope of the 60 appended claims.

I claim:

1. A switch device of the class described comprising a bracket, a lever pendulously supported from said bracket, a circuit closing device comprising a receptacle having 70 fixed contacts and a mercury contact carried by the end of the pendulously supported lever, a guard for said receptacle in the form of a fixed channel member of U-shaped 75 cross-section within which the receptacle is disposed, and thermostat operated means for controlling the movement of said pendulously supported lever.

2. In a device of the class described, a pivoted lever, a frangible contact containing 80 receptacle carried by said lever, and a pivoted fork device adapted to be swung to a position to dispose the prongs thereof to opposite sides of said lever to prevent swinging movement of the latter.

3. A switch device of the character described comprising a pivoted lever, a thermostat operatively connected with said lever for imparting swinging movement thereto, an arm pivoted to said lever, a switch comprising a receptacle having fixed contacts and containing a shiftable contact for cooperation with said fixed contacts, said switch being carried by said arm, and a pin and slot connection between said arm and said lever 85 for securing the arm and consequently the switch in different pivotally adjusted positions relatively to the lever.

4. A switch device of the character described comprising a pivoted lever, a thermostat operatively connected with said lever for imparting swinging movement thereto, an arm pivoted to said lever, a switch comprising a receptacle having fixed contacts and containing a shiftable contact for cooperation with said fixed contacts, said switch being carried by said arm, said arm having an elongated arcuate slot concentric with respect to the pivotal connection between said arm and said lever, and screw clamp means carried by the lever and extending through said slot for cooperation with said arm to secure the latter and consequently the switch in different pivotally adjusted positions relatively to the lever.

In testimony whereof I hereunto affix my signature.

CHARLES A. CYPHERS.
